UNITED STATES PATENT OFFICE

97,131

DESIGN FOR A HEAT INSULATED JUG

Joseph L. Hemp, Macomb, Ill., assignor to Hemp & Company Corporation Manufacturers of Sheet Metal Goods, Macomb, Ill., a corporation of Missouri

Application July 2, 1934, Serial No. 52,425

Term of patent 14 years

To all whom it may concern:

Be it known that I, Joseph L. Hemp, a citizen of the United States, residing at Macomb, in the county of McDonough and State of Illinois, have invented a new, original, and ornamental Design for a Heat Insulated Jug, of which the following is a specification, reference being had to the accompanying drawing, forming a part thereof.

In said drawing—

Figure 1 is a front elevation of the heat insulated jug; and

Figure 2 is a plan view of the same.

I claim:

The ornamental design for a heat insulated jug as shown.

JOSEPH L. HEMP.
